UNITED STATES PATENT OFFICE.

WILLIAM ADAMS GUPTILL, OF MAIDSTONE, VERMONT.

RAIL TIE AND FASTENER.

1,134,737.

Specification of Letters Patent.

Patented Apr. 6, 1915.

Application filed August 1, 1914. Serial No. 854,436.

To all whom it may concern:

Be it known that I, WILLIAM A. GUPTILL, a citizen of the United States, residing at Maidstone, in the county of Essex and State of Vermont, have invented a new and useful Improvement in Rail Ties and Fasteners, of which the following is a specification.

This invention relates to railroad appliances and more particularly to an improved cross tie and rail fastener.

One of the principal objects of the invention is to provide a cross tie with an improved rail fastener having means for securely locking the track rails against the tie.

An important object of the invention is to provide a fastener adapted to clamp the tie so firmly to the rail that all vibration will be reduced to a minimum, and also to provide means for taking up wear between the fastener and rail.

Another object of the invention is to provide an improved rail fastener capable of quick attachment, without the requirement of skilled labor or special tools.

A further object of the invention is to provide a device of the class described which will be simple, durable, efficient in operation and inexpensive to manufacture.

With these and other objects in view which will become apparent as the description proceeds, the invention resides in the construction, combination and arrangement of parts, hereinafter more fully described and claimed, and illustrated in the accompanying drawing, in which like characters of reference indicate like parts throughout the several figures, of which—

Figure 1 represents a side elevational view partly in section of the tie and fastener. Fig. 2 represents a top plan view thereof. Fig. 3 represents an end elevational view thereof. Fig. 4 represents a plan view of one end of the tie, the fastener being removed. Fig. 5 represents a sectional view taken longitudinally of the tie at one end thereof, showing the fastener in use with one form of fish plate. Fig. 6 represents a view similar to Fig. 5 showing the attachment in use with another form of fish plate. Fig. 7 represents a view similar to Fig. 5 showing the device in use with a shim. Fig. 8 represents a top plan view of the brace.

Referring more particularly to the drawing, the tie is of an inverted U-shape in cross section, and includes a top 5 and sides 6. A block 7 is secured within the tie near each

end thereof, by means of rivets or other suitable fastenings 8. The blocks are disposed at such a distance apart as to underlie the track rails. These blocks serve the double purpose of strengthening the tie, and of serving as anchoring means for the various fastener parts. As indicated the blocks are solid at their central portions, and are provided with extensions similar in cross section to the tie.

A fastening device is provided at each end of the cross tie. Each device includes a brace 10, a clamp 11, a binding wedge 12, a binding plate 13 and a locking wedge 14. The brace 10 is adapted to engage, at its inner end 15 which is substantially cup shaped, against the web of the rail. The brace is provided with a central depending boss 16 which engages in an opening 17 in top 5 of the tie. The opening is provided with oppositely disposed extensions 18, and these extensions overlie a transversely disposed groove 19 provided in block 7. The brace is provided with a transversely disposed vertical slot 20, in which the bolts 21 are disposed. Said bolts are provided with heads 22 at their lower ends. In securing the brace to the tie, the bolts are slid together at the center of slot 20 so that heads 22 may be projected through the openings 17 into the groove 19. The bolts are then forced away from each other in opposite directions so that the shanks of the bolts slip into the extensions 18 of the openings 17, while the heads of said bolt extend into the ends of groove 19 and engage the under side of top 5 of the tie on opposite sides of the extensions 18.

Brace 10 on its upper surface is provided with a transversely disposed raised portion or boss 23. This boss supports a locking plate 24, provided at its ends with openings through which the upper ends of bolts 21 extend, when said bolts are in final position. The nuts 25 are turned down upon the upper ends of the bolts and the locking plate 24 is then bent upwardly at its ends to provide a lock for the nuts.

The tie and block is provided on the opposite side of rail 9 from the brace, with an opening having a vertical inner wall 26, and an inclined outer wall 27. Within this opening against the vertical wall 26 the clamp 11 is disposed. Said clamp is provided with a shoulder 28 at its lower end adapted to engage in an enlargement of the

opening to prevent vertical movement of the clamp. The upper end of the clamp is bent into a hook as at 29, said hook projecting toward the rail and overhanging the base flange thereof. The binding plate 13 is bent transversely midway of its length, and is provided with a central opening 30. The plate is engaged over clamp 11, with the latter projecting through opening 30. The inner end of the plate indicated at 31 lies flat upon the adjacent base flange of the rail. The binding wedge 12 is provided with a vertical edge 32 adapted to engage against clamp 11 and is provided with an inclined edge 33 adapted to co-act with inclined wall 27 of the opening. The upper portion of the wedge is provided with a head 34 overhanging the two sides and rear faces of said wedge. The front straight edge 32 of the wedge is connected with head 34 by an inclined portion 35. The outer end of binding plate 13 rests against this inclined portion 35 of the wedge. The wedge may be solid or hollow, as the circumstances of the case may best decide.

The locking wedge 14 is disposed between hook portion 29 of the clamp, and the inner end 31 of the binding plate after the binding wedge 12 and the binding plate have been put in position, and is driven home whereby to force said plate against the base flange of the rail. This action clamps the rail against the brace 10, and against the top 5 of the tie. The smaller end of the wedge is bifurcated, and after the wedge is driven home one of the prongs formed by the bifurcation is bent upwardly as at 36 into engagement with hooked portion 29 of the clamp. The wedge is thus prevented from becoming disengaged from its wedging position.

The fastening devices illustrated in Figs. 5 and 6 are identical with the one described except as to the proportions of the brace, 45 and the binding plate and hooked portions of the clamp. These parts are so proportioned as will be understood, as to snugly engage the different forms of fish plates used in the particular cases. As indicated in the figures mentioned, the cup shaped ends 15 of braces 10 are shortened in each instance to engage against the adjacent face of the particular form of fish plate used. The inner end 31 of binding plate 13 in each case 50 is shortened so as not to bear against the web of the adjacent fish plate, and the hooked portions of the clamps 11 are likewise shortened, while the clamps themselves are made longer to compensate for the thickness of the base portions of said adjacent fish plates.

In Fig. 8 the fastening device is shown as in use with a shim indicated at 37. The shim is provided with openings of a similar shape to and registering with the openings

in the top of the tie, so that the various elements of the fastening device may pass through the shim into engagement with the block, in the manner already described.

In disassembling the fastener, after the same has been locked in position against a rail, the arm or prong 36 is bent downwardly with a hammer or other suitable instrument, and the locking wedge removed. The binding wedge is then forced upwardly by means of a pinch bar or other suitable instrument, and the clamp and binding plate then removed. Should the head of the binding wedge break off during the process of lifting the wedge, the cored opening in the wedge will provide means whereby the wedge may be engaged by a suitable hook for lifting said wedge.

From the foregoing description it will be readily understood that the device may be quickly assembled and disassembled, and no special tools will be required in the operation. It is also evident that the device will positively clamp the rails against the ties, in an immovable position relatively thereto, thus providing a very efficient and safe fastening device.

One of the notable advantages of operation of this device is the fact that by driving in the locking wedge 14 from time to time, the wear which might occur between the rail and the fastening means or the tie, may be effectively taken up, so that the rail will at all times be positively and immovably locked to the tie. In this manner the vibration caused by the passage of rolling stock over the track, will be reduced to a minimum.

Although I have described the preferred embodiment of my invention, I may desire to make such changes in the construction, combination and arrangement of parts thereof as do not depart from the spirit of the invention and the scope of the appended claims.

I claim:

1. A device of the class described including a cross tie of an inverted U-shape in cross section, a block disposed within the tie at each end thereof and secured thereto, a brace disposed on the cross tie and adapted to engage the outer side of a track rail, means for securing said brace to the tie, a clamp disposed in an opening provided in the tie and block on the opposite side of the rail from said brace, a binding wedge adapted to be disposed in said opening against the clamp, a binding plate adapted to be engaged over the clamp, the ends of the plate adapted to engage the base flange of the rail and the binding wedge respectively, and a locking wedge, adapted to engage said clamp and binding plate for locking the parts in position.

2. A device of the class described includ-

- ing a cross tie, a block secured thereto, a brace disposed on the tie and adapted to engage a track rail, said brace at its engaging ends being cup shape, a boss depending from 5 the brace and adapted to extend through an opening in the tie, said block provided with a groove underlying the opening in the tie, said tie opening having oppositely disposed extensions alining with the groove, said 10 brace provided with a transverse slot therein, bolts disposed in said slot and provided with headed ends, said headed ends adapted to be disposed in said groove in engagement with the tie adjacent the extensions of the 15 opening in said tie, said bolts extending through said brace, a locking plate through which said bolts are adapted to be extended, said locking plate adapted to maintain said bolts in engagement with the tie.
- 20 3. A device of the class described including a cross tie, a block secured thereto, a brace secured to the tie and adapted to engage one side of the track rail, said tie and block provided with an opening on the opposite side of the rail from the brace, said opening adjacent the rail having a vertical wall, and having an inclined wall opposite said vertical wall, a clamp disposed in said opening against the vertical wall, a binding 25 wedge disposed in the opening in engagement with the clamp and with the inclined wall of the opening, said clamp provided with a hook portion adapted to overhang the base flange of the rail, a binding plate adapted to be engaged over said clamp with its ends overhanging the base flange and the binding wedge, and a locking wedge adapted to be engaged between said binding plate and hooked portion of the clamp whereby 30 to lock said binding plate against said rail flange and against said wedge.
- 40 4. A device of the class described comprising a tie having a block secured thereto, a brace secured to the tie and adapted to engage one side of a track rail, a clamp disposed in an opening in the tie and block positioned on the opposite side of the rail from said brace, means for maintaining said clamp in position, a binding plate, and means adapted to engage said clamp and binding plate for locking the latter against the rail and against the clamp retaining means.
- 45 5. A device of the class described including a cross tie, a clamp disposed in an opening therein and having a hook at its upper end, a binding plate, means for engaging 50
- said hook and binding plate whereby to force the latter into locking position against the track rail, and a binding wedge for retaining said clamp in position, said wedge 60 having a vertical edge disposed against said clamp, and having an inclined edge, adapted to coact with an inclined edge of the opening in the tie, for wedging said clamp in position, said wedge having a head 65 formed on its upper end, said binding plate adapted to engage against said wedge to maintain the latter in position.
6. A device of the class described including a cross tie, a clamp disposed in an opening in the tie, a wedge for maintaining the clamp in the opening, a binding plate adapted to engage at one end against a track rail and at the other against said wedge, and a locking wedge for engaging the clamp and 70 binding plate for locking the track rail and binding wedge in position.
7. A device of the class described including a tie, a clamp engaging the tie and provided with a hooked portion, a binding 75 wedge engaging the tie and clamp for holding the latter in place, a binding plate engaging the clamp and binding wedge, said plate being disposed partially over a track rail, and means adapted to be engaged between the hooked portion of the clamp and the binding plate for locking the same 80 against the rail and wedge.
8. A device of the class described including a cross tie, a clamping element engaging 85 the tie adjacent a track rail, a binding wedge engaging the tie and clamping element, said wedge provided with a head having an inclined portion, an angular plate adapted to engage the rail and the inclined portion of the wedge head, and co-acting means between said clamping element and plate for locking the latter in position.
9. A device of the class described including a cross tie, a brace secured thereto and 90 adapted to engage one side of a track rail, a binding plate adapted to engage the other side of the rail, means for locking the binding plate in position, and means adapted to engage said binding plate and the locking 95 means therefor for taking up wear between the rail and binding plate and brace.
